Babcock & Wilcox Company, Newark, N. J.,
a corporation of New Jersey

Application January 28, 1939, Serial No. 253,240

10 Claims. (Cl. 122—501)

The present invention relates to improvements in the construction and operation of fluid heating apparatus, and more particularly to liquid heaters and vaporizers in which cores or displacers are employed in some of the fluid heating tubes to reduce the effective cross-sectional flow area thereof and thereby increase the liquid contact with the tube walls, to minimize the possibility of overheating of the tubes. The general object of our invention is the provision of an improved construction and arrangement of a core for the purpose described. A more specific object is the provision of a fluid heating tube core construction which is characterized by its effectiveness in use, simplicity of design, relatively low cost of construction, and ease of installation and removal. A further specific object is the provision of a vapor generating tube core arrangement which provides the desired reduction in effective flow area and permits of a high rate of heat transfer to the liquid in the tube over substantially all of its surface and particularly from the portion of the tube wall most liable to overheating, and insures maximum heat absorbing capacity within safe operating limits.

The various features of novelty which characterize our invention are pointed out with particularity in the claims annexed to and forming a part of this specification. For a better understanding of the invention, its operating advantages and specific objects attained by its use, reference should be had to the accompanying drawings and descriptive matter in which we have illustrated and described a preferred embodiment of the invention.

Of the drawings:

Fig. 1 is a sectional elevation of a steam boiler unit in which the invention may be employed;

Fig. 2 is an enlarged view of the furnace floor tube shown in Fig. 1;

Figs. 3 and 4 are sectional views taken on the lines 3—3 and 4—4 respectively of Fig. 2; and

Fig. 5 is a longitudinal section through the wall of the flexible tubing.

In Fig. 1 is illustrated a water tube steam boiler of the integral furnace type, such as is disclosed in U. S. Patent 1,999,984. The steam boiler illustrated comprises a vertically disposed bank of steam generating tubes 10 extending between horizontally arranged upper and lower drums 11 and 12 respectively. The tube bank and drums are arranged along one side of the boiler setting with the remaining portion thereof serving as a furnace chamber 13 which is sep-

arated from the space containing the tube bank by a row of partition-forming tubes 14 except at the rear end. As indicated in Fig. 1 the furnace illustrated is fired by a plurality of fluid fuel burners 15 arranged in the front wall. The furnace floor is water cooled by a row of water tubes 20 extending at a slight horizontal inclination from the lower drum 12 to a header 21 below the outer side wall of the furnace. A row of water tubes 22 extends along the outer side wall and roof of the furnace and connect the header 21 to the upper drum 11. The tubes 20 and 22 are similarly spaced apart longitudinally of the furnace. The spaces between the floor tubes 20 are closed by floor blocks of heat resistant material held in position on and transmitting heat from the furnace chamber to the tubes 20.

In normal operation a portion of the tubes at the front end of the tube bank 10 serves as down-comers, permitting a water flow from the upper drum 11 to the lower drum 12. The lower drum supplies all of the floor tubes 20 with water which is delivered to the side wall header 21 and redistributed therein to the tubes 22, through which it flows together with any steam generated to the upper drum 11. The rate of fluid flow through the floor tubes 20 depends upon the pressure differential created by the difference in densities of the fluid in the vertical conduit portions connected to the opposite ends thereof. Under certain operating conditions the rate of fluid circulation through the floor tubes 20 may be so low as to fail to displace steam bubbles collecting in the upper portions of the floor tubes.

In order to maintain the wall temperature of vapor generating tubes within the desired range, it is important that the internal peripheral surface of the tubes, and particularly the portion where vapor bubbles tend to collect, and especially so if these wall portions have the highest rate of heat input, be maintained wet with liquid for the most effective heat transfer conditions. This maintenance of wetness is particularly difficult when the tube is arranged in a horizontal or horizontally inclined position, as when used as a floor tube, as the vapor generated therein tends to separate and concentrate in the uppermost portion of the tube which is subject to the most intense heating.

In accordance with our invention each of the floor tubes 20 in which displacement of stagnant steam bubbles or prevention of dry spots is desired, is provided with a core or displacer for re-

ducing the effective fluid flow area therethrough arranged therein so as to provide an effective flow area causing an increased liquid contact with the upper part of the tube wall. As shown in Fig. 2, the ends of each tube 20 are expanded into the drum 12 and header 21, the inner side of the drum wall being counterbored as indicated. The tube core consists of a body section 25, preferably formed of flexible steel tubing, as shown in Fig. 5, adapted to be put under tension. Each end of the core tubing is provided with a fastening device for detachably securing the core in its desired position. As shown, the drum or upstream end of the tubing has the larger end of a streamlined plug 26 inserted therein and held in position by a pin 27 extending through the tubing and plug. The plug 26 is formed with a narrow projecting hook 28 extending beyond and around the expanded end of the tube 20. The hook portion 28 is adapted to engage a bar 29 welded on the inner side of the drum wall below the tube opening. The plug 26 is cut away, as indicated in Fig. 2, to provide a small opening 30 connecting the interior of the tube 20 and the interior of the tubing 25. The header or downstream end of the tubing 25 is also provided with a streamlined plug 31 having a more gradual taper than the plug 26, and which is held in position therein by a pin 32 and terminates in a projecting hook 33. The plug 31 is also cut away to provide a passage 34 similar to the passage 30 at the other end of the tubing.

The described core construction facilitates the installation and arrangement of the cores in the tubes. Each of the cores is brought into the drum 12 through a man-hole in one of the drum end walls and inserted into the corresponding floor tube until the hook 33 extends over the header end of the tube and contacts with the wall of the header 21 below the tube end. The flexible tubing of the core is then put under tension and the hook 28 sprung over the bar 29, the flexible tubing being of suitable length so that the core will be under tension after being sprung into position to aid in keeping it in that position. The core and associated parts are constructed and arranged so that the core will extend along the bottom of the floor tubes. This eccentric position relative to the tube is preferable as it displaces the flowing water upwardly and forces it into contact with the upper portion of the tube wall moving any stagnant steam bubbles and wetting the wall portion which is more liable to be overheated than the portion contacted by the core. In effect, the central axis of the effective flow area of the tubes is raised to a point above the geometrical center of the tube. The streamlining of the plugs 26 and 31 tends to prevent liquid flow resistance which would reduce the rate of circulation through the tube 20 by minimizing eddy currents at the ends of the core. The core openings 30 and 34 aid in maintaining the core in its intended position on the tube bottom, by permitting the entry of water into the tubing 25 and thus offsetting any tendency of the core to float upwardly. The core construction described is adapted for use in not only various types of existing fluid heaters for improving the circulation therein, but also new fluid heater installations where for various reasons tube diameters are employed which render the use of cores advantageous.

While in accordance with the provisions of the statutes we have illustrated and described herein the best form of the invention now known to us,

those skilled in the art will understand that changes may be made in the form and arrangement of the device disclosed without departing from the spirit of the invention covered by the 5 claims, and that certain features of the invention may sometimes be used to advantage without a corresponding use of other features. For example, the core can be made progressively increasing in cross-section towards its downstream 10 end, where the quantity of vapor bubbles present tends to increase towards that end.

We claim:

1. A flow area reducing core adapted to be inserted in a fluid conduit comprising a hollow 15 elongated elastic body member and means mounted on each end of said body member for detachably holding the core under tension in position in the conduit.

2. A flow area reducing core adapted to be inserted in a fluid conduit comprising an elongated body member formed of flexible tubing adapted to be put under tension and end members connected to the ends of said flexible body member and having a hook-shaped extension for holding the core in position.

3. A flow area reducing core adapted to be inserted in a fluid conduit comprising an elongated body member formed of flexible tubing adapted to be put under tension and a streamlined end member mounted in each end of said flexible body member and having a hook-shaped extension for detachably holding the core in position in the fluid conduit.

4. A flow area reducing core adapted to be inserted in a fluid conduit comprising an elongated body member formed of flexible tubing and a streamlined end member mounted in each end of said flexible body member and having a hook-shaped extension for holding the core in position, said body member having an opening therein for the entry of fluid from the fluid conduit.

5. In a fluid heater, a pair of spaced fluid containers, a tubular fluid conduit having its opposite ends connected to said containers, and a flow area reducing core having a hollow elongated elastic body member arranged in said tube and having end fastening means thereon extending into and detachably engaging said containers for holding said body member under tension in a predetermined position in said fluid conduit.

6. In a fluid heater, a pair of spaced fluid containers, a tubular fluid conduit having its opposite ends connected to said containers, a flow 55 area reducing core formed of flexible tubing adapted to be put under tension arranged in said conduit, and fastening means on each end of said core arranged to extend into said containers for holding said core under tension in said conduit.

7. In a fluid heater, a pair of spaced fluid containers, a tubular fluid conduit having its opposite ends connected to said containers, a flow 65 area reducing core formed of flexible tubing and eccentrically arranged in said conduit, and fastening means on each end of said core arranged to extend over the ends of said conduit and engage the walls of said containers to hold said core in position in said conduit.

8. In a fluid heater, a pair of spaced fluid containers, a substantially horizontal floor tube having its opposite ends connected to said containers, a flow area reducing core formed of flexible tubing and eccentrically arranged along the bottom

of said tube, and fastening means on each end of said core arranged to hold said core in position.

9. In a fluid heater, a pair of spaced fluid containers, a substantially horizontal elongated floor tube having its opposite ends expanded into said containers, a flow area reducing core formed of flexible tubing and eccentrically arranged along the bottom of said tube, and hook-shaped fastening means on each end of said core arranged to extend into and engage said containers for holding said core in position under tension.

10. In a fluid heater, a pair of spaced fluid containers, a fluid heating tube having its opposite

ends connected to said containers and normally exposed to relatively high temperatures along one side thereof, and a flow area reducing core removably mounted in said tube and including a continuous length of flexible metallic tubing of substantially uniform diameter extending along the length of said tube and means for holding said tubing in spaced relation with the heat absorbing side of said tube including means for fastening said tubing at least at one end to one of said fluid containers.
